(57) **CLAIM**

The ornamental design for a leg assembly as shown and described.

DESCRIPTION

FIG. 1 is a side view of a first embodiment of a leg assembly, with the opposite side view being a mirror image thereof; FIG. 2 is a first end view of the leg assembly shown in FIG. 1;

FIG. 3 is a second end view of the leg assembly shown in FIG. 1 opposite the first end view;

FIG. 4 is a top view of the leg assembly shown in FIG. 1; FIG. 5 is a bottom view of the leg assembly shown in FIG. 1;

FIG. 6 is a top perspective view of the leg assembly shown in FIG. 1;

FIG. 7 is a bottom perspective view of the leg assembly shown in FIG. 1;

FIG. 8 is a side view of a second embodiment of a leg assembly, with the opposite side view being a mirror image thereof;

FIG. 9 is a first end view of the leg assembly shown in FIG. 8;

FIG. 10 is a second end view of the leg assembly shown in FIG. 8 opposite the first end view;

FIG. 11 is a top view of the leg assembly shown in FIG. 8; FIG. 12 is a bottom view of the leg assembly shown in FIG. 8;

FIG. 13 is a top perspective view of the leg assembly shown in FIG. 8; and,

FIG. 14 is a bottom perspective view of the leg assembly shown in FIG. 8.

The broken lines showing openings in FIGS. 1, 4, 6-8, 13 and 14 are directed to environment and form no part of the claimed design.

1 Claim, 8 Drawing Sheets
